UNITED STATES PATENT OFFICE

ARTHUR O. AUSTIN, OF NEAR BARBERTON, OHIO, ASSIGNOR, BY MESNE ASSIGNMENTS, TO THE OHIO BRASS COMPANY, OF MANSFIELD, OHIO, A CORPORATION OF NEW JERSEY

INSULATOR PIN

Application filed August 10, 1928. Serial No. 298,828.

This invention relates to insulator pins and has for one of its objects the provision of a soft metal tip for insulator pins which will remain firmly fixed to the pin and not be loosened or distorted by the mechanical stress to which the pin is subjected.

A further object is to provide soft metal tips for insulator pins having reinforcements of more rigid metal. A further object is to provide an insulator pin which shall be of improved construction and operation. Other objects and advantages will appear from the following description.

The invention is exemplified in the combination and arrangement of parts shown in the accompanying drawing and described in the following specification, and it is more particularly pointed out in the appended claims.

20 In the drawing:

Fig. 1 is a part elevation and part section showing one form of reinforcing cage comprised in the present invention.

25 Fig. 2 is a section on line 2—2 of Fig. 1.
Fig. 3 is a section on line 3—3 of Fig. 1.

Fig. 4 is a part elevation and part section of a pin tip having one embodiment of the invention applied thereto.

30 Fig. 5 is a part elevation and part section showing another form of reinforcement.

Fig. 6 is a plan of the device shown in Fig. 5.

35 Fig. 7 is a view similar to Fig. 4 but showing the reinforcement illustrated in Fig. 5 applied to a pin tip.

In providing a lead tip for insulator pins, it has been customary to cast the lead tip over the end of the steel pin. Where the loads are light, this has frequently been satisfactory. In many cases, however, there is little bond between the central steel pin and the lead tip so that the latter becomes loose on the steel center or flows.

40 45 If a very strong bond between the two is desired, it is necessary to roughen the steel center very carefully or amalgamate the lead to the same. Where the central steel member is rather small compared to the diameter of the tip, or the thickness of lead is much

in excess of that required for the lead thread fitting into the pin hole of the insulator, it will be found that the lead will flow readily or loosen from the central spindle.

55 Where lead tips are applied to old pins in the field, it is practically impossible to amalgamate the lead to the pin tip. It is, however, desirable to hold it tightly to the pin. This result may be accomplished by using an iron or steel metal cage or other reinforcing member such as a pressed metal reinforcement or wire helix. These reinforcing members are preferably tinned or coated with zinc or lead which will amalgamate with the material used to form the tip casting. It will be seen that this reinforcing material distributed through the lead will tend to prevent it from becoming loose from the central member. In some cases the reinforcement, in addition to adding rigidity where the lead part is thick, may be used to advantage in displacing the lead which usually costs considerably more than steel or other reinforcing metal. In some cases, the reinforcing material will add sufficient strength so that a lead thread may be formed inside a thimble, making the reinforced thimble removable.

60 65 70 75 80 There are many forms of the reinforcements which may be provided with lugs or projections or be so formed at different points that it will center itself during the casting of the tip. The reinforcing has a large area in contact with the lead, and forms an efficient bonding and reinforcing of the tip.

85 90 95 100 In the form of the invention illustrated in Figs. 1 to 4 inclusive, the numeral 10 designates the end of a metallic insulator pin, the end of the pin being roughened by means of grooves 11 formed therein. Other forms of irregular surfaces, may of course, be employed. A lead, or other soft metal tip, 12 is cast upon the end of the pin 11 and has embedded therein a reinforcing cage 13. The reinforcing cage may be forged, cast, stamped or otherwise formed from iron, steel or other suitable metal having greater rigidity than the lead of the tip 12. The member 13 is in the form of an open-work cage which surrounds the end of the pin and is spaced out

wardly therefrom a sufficient distance so that when the tip 12 is cast in place on the pin, the reinforcing cage will be embedded in the soft metal of the tip. The upper end of the tip is preferably provided with an overhanging flange or lugs 14 which rest on the end of the pin and support the tip. This not only provides means for holding the cage in place while the tip is being poured, but also 10 provides a support of relatively rigid metal for the material of the lead tip.

The weight of the insulator and line is transmitted to the reinforcing cage and in turn, to the end of the tip, partly through contact of the lead with the pin and partly through the flange 14. The outer surface of the tip may be threaded, as shown, to receive complementary threads on an insulator.

In the form of the invention shown in Figs. 5, 6 and 7, the pin 10 is provided with circumferential grooves 11 and a lead tip 12, similar to that shown in Fig. 4. The tip 12, however, is reinforced by a wire 15 wound in the form of a helix and surrounding the end of the pin. It will be seen from Fig. 6 that the wire of the helix is bent inwardly at spaced intervals as shown at 16 and as shown in Fig. 7, the inwardly bent portions 16 engage the surface of the pin 10. In this way the reinforcing helix is held in proper spaced relation to the pin while the lead is being cast about the end of the pin.

Various other forms of reinforcement for lead tips may be made without departing from the spirit and scope of the invention.

I claim:

1. An insulator pin, comprising a spindle, a soft metal tip enclosing the end of said spindle, and a reinforcing member embedded in said tip, said reinforcing member having contact with said spindle to brace said reinforcing member against said spindle.

2. An insulator pin, comprising a spindle, a soft metal tip enclosing the end of said spindle, and an open-work reinforcing cage embedded in said tip, said cage having a portion thereof engaging said pin in position to hold said tip against movement in one direction lengthwise of said spindle.

3. An insulator pin, comprising a spindle, a soft metal tip formed upon the end of said spindle, an open-work reinforcing cage of former metal embedded in the metal of said tip and having inwardly projecting portions for holding said cage outwardly in spaced relation with said spindle.

4. An insulator pin, comprising a spindle, a reinforcing coil surrounding the end of said spindle and having an inner diameter greater than the outer diameter of said spindle, said coil having portions thereof bent inwardly to engage the surface of said spindle and holding said coil in position on said spindle, and a soft metal tip surrounding

said spindle and having said coil embedded therein.

In testimony whereof I have signed my name to this specification this 7th day of August, A. D. 1928.

ARTHUR Q. AUSTIN.

CERTIFICATE OF CORRECTION.

Patent No. 1,894,340.

January 17, 1933.

ARTHUR O. AUSTIN.

It is hereby certified that error appears in the printed specification of the above numbered patent requiring correction as follows: The name of the patentee "Arthur O. Austin" should be inserted at the end of the drawing; and that the said Letters Patent should be read with this correction therein that the same may conform to the record of the case in the Patent Office.

Signed and sealed this 22nd day of August, A. D. 1933.

M. J. Moore.
